(57) **CLAIM**

The ornamental design for a concentric ring-shaped free weights set, as shown and described.

DESCRIPTION

FIG. 1 is a top, front perspective view of a concentric ring-shaped free weights set having three nested, different-sized ring-shaped free weights (e.g., the three ring-shaped free weights being designated as “small,” “medium,” and “large” for purposes of this application, with “small” referring to the smallest ring-shaped free weight of the set, “large” referring to the largest ring-shaped free weight of the set, and “medium” referring to the ring-shaped free weight sized between the smallest and the largest of the set), showing our new design in nested configuration;

FIG. 2 is a front elevation view of the concentric ring-shaped free weights set of FIG. 1;

FIG. 3 is a left side elevation view of the concentric ring-shaped free weights set of FIG. 1;

FIG. 4 is a rear elevation view of the concentric ring-shaped free weights set of FIG. 1;

FIG. 5 is a right side elevation view of the concentric ring-shaped free weights set of FIG. 1;

FIG. 6 is a top plan view of the concentric ring-shaped free weights set of FIG. 1;

FIG. 7 is a bottom plan view of the concentric ring-shaped free weights set of FIG. 1;

FIG. 8 is an exploded top, front perspective view of the concentric ring-shaped free weights set of FIG. 1;

(Continued)

FIG. 9 is a top, front perspective view of the small ring-shaped free weight of the concentric ring-shaped free weights set of FIG. 8;

FIG. 10 is a front elevation view of the small ring-shaped free weight of FIG. 9;

FIG. 11 is a left side elevation view of the small ring-shaped free weight of FIG. 9;

FIG. 12 is a rear elevation view of the small ring-shaped free weight of FIG. 9;

FIG. 13 is a right side elevation view of the small ring-shaped free weight of FIG. 9;

FIG. 14 is a top plan view of the small ring-shaped free weight of FIG. 9;

FIG. 15 is a bottom plan view of the small ring-shaped free weight of FIG. 9;

FIG. 16 is a top, front perspective view of the medium ring-shaped free weight of the concentric ring-shaped free weights set of FIG. 8;

FIG. 17 is a front elevation view of the medium ring-shaped free weight of FIG. 16;

FIG. 18 is a left side elevation view of the medium ring-shaped free weight of FIG. 16;

FIG. 19 is a rear elevation view of the medium ring-shaped free weight of FIG. 16;

FIG. 20 is a right side elevation view of the medium ring-shaped free weight of FIG. 16;

FIG. 21 is a top plan view of the medium ring-shaped free weight of FIG. 16;

FIG. 22 is a bottom plan view of the medium ring-shaped free weight of FIG. 16;

FIG. 23 is a top, front perspective view of the large ring-shaped free weight of the concentric ring-shaped free weights set of FIG. 8;

FIG. 24 is a front elevation view of the large ring-shaped free weight of FIG. 23;

FIG. 25 is a left side elevation view of the large ring-shaped free weight of FIG. 23;

FIG. 26 is a rear elevation view of the large ring-shaped free weight of FIG. 23;

FIG. 27 is a right side elevation view of the large ring-shaped free weight of FIG. 23;

FIG. 28 is a top plan view of the large ring-shaped free weight of FIG. 23; and,

FIG. 29 is a bottom plan view of the large ring-shaped free weight of FIG. 23.
